CLAIM

The ornamental design for a handle and ball pet toy, as shown and described.

DESCRIPTION

FIG. 1 is a front perspective view of a handle and ball pet toy embodying my new design;

FIG. 2 is a front elevational view thereof of FIG. 1;

FIG. 3 is a rear elevational view thereof of FIG. 1;

FIG. 4 is a left side elevational view thereof of FIG. 1;

FIG. 5 is a right side elevational view thereof of FIG. 1; and,

FIG. 6 is a top elevational view thereof of FIG. 1.

The broken lines shown in the drawings are for illustrative purposes only and form no part of the claimed design.
